C. V. MONSON.

WINDOW SASH FASTENER.

APPLICATION FILED MAY 21, 1917.

1,255,548.

Patented Feb. 5, 1918.

FIG. 1.

FIG. 2.

FIG. 3.

INVENTOR.
Chas. V. Monson.
BY
Geo. St. James.
ATTORNEY.

UNITED STATES PATENT OFFICE.

CHARLES V. MONSON, OF DULUTH, MINNESOTA.

WINDOW-SASH FASTENER.

1,255,548.

Specification of Letters Patent.

Patented Feb. 5, 1918.

Application filed May 21, 1917. Serial No. 169,820.

To all whom it may concern:

Be it known that I, CHARLES V. MONSON, a citizen of the United States, residing at Duluth, in the county of St. Louis and 5 State of Minnesota, have invented certain new and useful Improvements in Window-Sash Fasteners, of which the following is a specification, reference being had therein to the accompanying drawing.

10 This invention relates to sash locks for windows. The principal object of the invention is to produce simple and strong means for fastening the upper and lower sash of a window together and securely 15 holding same with the joint between the sashes tightly closed.

Another object is to provide a device of 20 this character having a means whereby the window may be firmly united and locked when the two parts of the sash are somewhat separated or the window partly open.

These and other objects will become evident in the further description of the device.

25 In the accompanying drawings forming part of this application and in which like reference characters indicate like parts,

Figure 1 is a top plan view of the improved lock or fastener uniting the two 30 parts of the sash when closed.

Fig. 2 is a similar view illustrating the catch in its unlocked position.

Fig. 3 is a vertical sectional view through 35 the center line of the bolt of the fastener, and

Fig. 4 is a reduced front elevation of that portion of the fastener attached to the lower rail of the upper half of the window sash and illustrating in active position, the support for the lower sash when open.

1—1 represents two clips spaced apart 40 opposite each other and fastened by means of screws 2 to the upper face of the upper rail 6 of the lower sash. These clips slidably hold between them, the horizontally reciprocal bolt 3, which is scarfed longitudinally 45 its edges, forming a stepped portion 4 and into which stepped portion the upwardly and inwardly extending lips 5 of the clips 50 project, thus forming a secure and substantial guide for the bolt.

The reciprocal motion of the bolt 3 is limited in both directions by the virtually adjustable L-shaped bolt 7—8 operative within 55 the rectangular shaped through slot 9 in the horizontally reciprocal bolt 3.

7 represents the horizontal portion of the bolt 7—8 which is of a size to freely fit within the slot 9 when properly adjusted thereto and as shown in Figs. 1 and 3. The 60 vertical portion 8 of the bolt, and which answers as the operating handle thereof, is hollow as at 10 and in which extends an elongated screw 11, a spiral spring 12 being mounted about the screw 11 intermediate 65 the head thereof and the bottom wall 13 of the hole, for normally holding the bolt in its depressed position.

The screw 11 passes through the bottom wall 13 of the hole 10 and is screwed into 70 the rail 6 as shown in Fig. 3.

By raising the bolt 7—8 against the expansive action of the spring 12, it may be brought to a level above the surface of the bolt 3 and turned at any desired angle 75 thereto, as shown in Fig. 2, and allowed to rest upon the upper surface of the bolt 3, during which position of the bolt 7—8, the bolt 3 may be slid back or forth longitudinally as desired, a suitable projecting 80 handle 14 for such purpose being formed integral with the bolt 3.

In line with the slot 9 in the bolt 3 and in the forward end thereof, is a notch 15 having an inclined bottom 16 therein, which 85 inclines upwardly toward the forward end of the bolt, the extreme upper corner of the forward end of the bolt being slightly rounded as at 17 for ready engagement with the coöperating portions of the fastener 90 hereinafter described.

An upwardly bowed catch or keeper 18 is rigidly fixed to the upper face of the lower rail 19 of the upper sash of the window by means of suitable screws 20. This 95 keeper is so positioned as to register with the end of the bolt 3 when the two rails 6 and 19 are opposite each other, as when the window is closed.

In the central upper arched portion of the keeper 18 is adjustably mounted a thumb screw 21. When the bolt 3 is adjusted to locking engagement with the keeper 18, the screw 21 may be extended downwardly into the notch 15 and when advanced in such 105 direction sufficiently far, the end of the screw will engage the inclined bottom 16 of the notch, such engagement having the normal tendency of drawing the two rails, 6 and 19 of the sash, tightly together by virtue 110 of the inclination of the bottom 16 of the notch 15, the same being regulated by the

force supplied to the screw 21, as is obvious. When the bolt 3 is fully advanced in its engagement with the keeper 18, the former may be locked in such position by the bolt 5 7-8 being turned to aline with the slot 9 and the portion 7 allowed to enter same, as shown in Figs. 1 and 3, and this without the necessity of adjusting the thumb screw 21, the latter being chiefly for more permanently locking the two parts of the window sash and making as near as possible a tight joint therebetween.

When the bolt 3 is withdrawn from engagement with the keeper 18, the bolt 7-8 15 must be raised from the slot 9 and preferably allowed to rest transverse the same, which permits of free and unobstructed operation of the window sash.

An additional attachment to the fastener 20 is provided in the form of a hollow rod 22, pivotally mounted as at 23, within one side of the keeper 18, this rod may be of any suitable length and carries, fixed to the free end thereof, a collar 24 having a thumb screw 25 therein and which latter is extendible within the interior of the rod. Telescopically mounted within the rod 22 is a rod 26, carrying upon its upper end a rectangular shaped keeper 27 and which keeper may be 30 adjusted vertically to any height desired within the limit of its adjustment and which keeper is designed to register with the engaging end of the bolt 3 when the vertical relation of the two halves of the window sash is changed from normal and whereby 35 the bolt 3 may be made to engage the keeper and the two halves of the sash firmly held in such adjusted position. Within the upper face of the keeper 27 is a thumb screw 28, similar, both as to construction and office, 40 to that of the thumb screw 21.

The rod 22 being pivotally mounted within the keeper 18 permits of its being tipped downwardly to one side and resting upon 45 the upper face of the lower rail of the upper half of the sash when not in use, otherwise it may be stood up as shown in Fig. 4 and allowed to rest upon its bent extension 50 29, which will support it centrally in line for engagement with the bolt 3. From the foregoing it is evident that by the use of the rod 22 and its coöperating parts, the window may be opened to various limitations and there securely locked when desired.

While I have shown certain specific forms of construction in illustrating this embodiment of my invention, it is evident that various modifications may be resorted 60 to without departing from the spirit thereof.

Having thus described the invention what I claim as new and desire to secure by Letters Patent is:

1. A window sash fastener comprising 65 two opposed guiding members spaced apart

and fixed to the upper face of the upper rail of the lower half of the window sash, a reciprocal bolt intermediate of the guiding members, having an inclined thumb-screw receiving slot in the upper face thereof, a keeper rigidly fixed to the lower rail of the upper half of the sash and adapted to register with the coöperating end of the bolt, means for limiting the longitudinal movement of the bolt and an adjustable thumb-screw within the keeper for coöperative engagement with the inclined slot in the bolt, whereby the two adjacent window sash rails may be simultaneously drawn together.

2. A window sash fastener comprising 80 two opposed guiding members spaced apart and fixed to the upper face of the upper rail of the lower half of the window sash, a reciprocal bolt intermediate of the guiding members, having an inclined thumb-screw 85 receiving slot in the upper face thereof, a keeper rigidly fixed to the lower rail of the upper half of the sash and adapted to register with the coöperating end of the bolt, vertically adjustable spring controlled 90 means for limiting the longitudinal movement of the bolt and locking same, and an adjustable thumbscrew within the keeper for drawing the adjacent rails of the sash together when in coöperative engagement 95 with the inclined slot in the bolt.

3. A window sash fastener of the character described, comprising a horizontally 100 slideable bolt carried by one portion of the sash, a keeper adapted to register with the bolt and fixed to the opposite portion of the sash and a second keeper supported upon the first mentioned keeper and registerable with the bolt and means for slidably raising and lowering the second keeper to accommodate 105 different opened conditions of the window.

4. A window sash fastener comprising a 110 slideable bolt mounted upon one portion of the sash, a pivoted bolt adjustable within the slideable bolt for locking the latter 115 against longitudinal movement, a fixed keeper upon the opposite portion of the sash adapted to register with the slideable bolt, a hollow supporting rod pivotally mounted upon the fixed keeper and an adjustable keeper vertically adjustably mounted upon the rod and adapted to register with the slideable bolt.

5. A window sash fastener comprising 120 two opposed guiding members spaced apart and fixed to the upper face of the upper rail of the lower half of the window sash, a reciprocal bolt intermediate of the guiding members, an upwardly arched keeper rigidly fixed to the lower rail of the upper 125 half of the sash and adapted to register with the coöperating end of the bolt, vertically adjustable spring controlled means mounted upon the bolt intermediate of the guiding member for limiting the longitudinal 130

movement of the bolt and means for simultaneously drawing the adjacent sash rails tightly together and locking same.

6. The combination with a window sash fastener of the character described, comprising a horizontally slideable bolt carried by one portion of the sash and a keeper adapted to register with the bolt and fixed to the opposite portion of the sash, of a support 10 pivotally mounted upon the first mentioned keeper and carrying a second keeper, said second keeper carrying means adapted to register with the bolt and being slideable vertically upon its support.

15 7. A window sash fastener comprising a horizontally slideable bolt mounted upon one

portion of the sash, a pivoted bolt vertically adjustable within the slideable bolt for locking the latter against longitudinal movement, a fixed keeper upon the opposite portion of the sash adapted to register with the horizontally slideable bolt and a telescopic adjustable keeper mounted upon the fixed keeper and adapted to register with the slideable bolt. 20

25 In testimony whereof I hereunto affix my signature in the presence of two witnesses.

CHARLES V. MONSON.
